UNITED STATES PATENT OFFICE

159,233

TRANSCRIBING MACHINE

Richard M. Somers, West Orange, N. J., assignor
to Thomas A. Edison, Incorporated, West
Orange, N. J., a corporation of New Jersey

Application February 5, 1949, Serial No. 699

Term of patent 14 years

(Cl. D56—4)

To all whom it may concern:

Be it known that I, Richard M. Somers, a citizen of the United States and a resident of the town of West Orange, in the county of Essex and State of New Jersey, have invented a new, original, and ornamental Design for a Transcribing Machine, of which the following is a specification, reference being had to the accompanying drawing, forming a part thereof.

In the drawing:

Figure 1 is a perspective view of the front and right side of a transcribing machine, showing my new design;

Figure 2 is a rear elevational view of this machine; and

Figure 3 is an elevational view of the left side of this transcribing machine.

I claim:

The ornamental design for a transcribing machine, substantially as shown.

RICHARD M. SOMERS.
